UNITED STATES PATENT OFFICE

JAMES C. DAWSON, OF WEBSTER GROVES, MISSOURI, ASSIGNOR TO ELMA N. DAWSON, OF WEBSTER GROVES, MISSOURI

LOOSE LEAF BINDER

Application filed February 28, 1931. Serial No. 519,136.

This invention relates to loose leaf binders and has for its principal object to improve the means for attaching certain types of "metals" to the backs and to give a better 5 mounting for the booster levers which open the rings, and also to form a rugged completely interlocked sub-assembly from which no parts can be shaken off in shipment. While the improved features are adaptable to all 10 types of binders, they are particularly useful in attaching the cheaper class of metals known as the "spring-cover type" to the book back. Such metals have usually been attached to the back by means of a rivet, but 15 there are many objections to this practice.

In the present invention, I provide each end of the metal with a fitting which permits the book binder to use the same cover attaching means as is used with more expensive spring- 20 back binders. This fitting not only binds the metal strongly to the back, but locks the individual parts of the binder so securely that they cannot be pulled loose by pulls or jerks upon the prongs, and it also provides a firm 25 support for the booster lever which heretofore has been flimsy due to the flexibility of the spring cover plate. Once having toolled-up to produce fittings for the expensive binders, a manufacturer can economically extend 30 their use with the more cheaper binders.

These and other objects will become apparent from the description and the appended drawings in which.

Fig. 1 is a perspective view of a binder incorporating the invention;

Fig. 2 is a vertical, longitudinal section through the end portion of the device showing the booster lever and booster lever support applied to binders of the spring cover plate 40 type;

Fig. 3 is a vertical, longitudinal section through the end portion of the device showing the booster lever and booster lever support applied to binders of the spring-back 45 type;

Fig. 4 is a bottom plan view of that portion of the binder illustrated in Fig. 2;

Fig. 5 is a transverse section on the line 5—5 of Fig. 2;

Fig. 6 illustrates in perspective the booster

lever, booster lever support and toggle plates of Figs. 2, 4 and 5.

Fig. 7 illustrates the modified form of wide thumb arm booster lever arranged to pass beneath the toggle plates and to lift them;

Fig. 8 illustrates the booster lever of Fig. 7 in perspective;

Fig. 9 illustrates a modified form of booster lever and booster lever support shown in top plan view;

Fig. 10 is a vertical, longitudinal section on the line 10—10 of Fig. 9;

Fig. 11 illustrates in perspective the booster lever and booster lever support shown in Fig. 9;

Fig. 12 illustrates a modified booster lever of Fig. 9 associated with the booster lever support as shown in Fig. 6;

Fig. 13 is a vertical, longitudinal section through a binder equipped with a modified form of booster lever arranged to pass beneath the toggle plates and to lift them; and

Fig. 14 illustrates in perspective the form of booster lever shown in Fig. 13.

Loose leaf binders of the type illustrated in Fig. 1 comprise a pair of articulated toggle plates 10 and 11 which bear paper-holding prongs 12 and 13. The outer edges of the plates may be gripped by the hooked margins 14 and 15 of the cover plate 16 in which case the cover plate 16 is itself a relatively stiff spring, or in binders of the spring back type, as shown in Fig. 3, the toggle plates may be gripped by the hooked margins of the spring back 17.

The support for the booster lever comprises an element 18 having a portion 19 adapted to close the end of the binder, a tongue 21 which is inserted into the binder and lies parallel to the back, and a cover plate engaging shoulder 22. When used with binders of the spring cover type, as shown in Figs. 2, 4 and 5, I cause the hooked margins 14 and 15 to engage the outer edges 23 and 24 of the tongue 21. The binder is held to the back by means of the loop 25 struck up from the back 26 which passes through the aperture 27 cut through the tongue. A slot 28 is cut through the end closure 19 to give clearance to the key 29.

which overlies the tongue 21 and passes beneath the loop 25.

In binders of the spring back type, an aperture 31 is cut through the back 32 and the tongue 33 of the supporting element 34 is provided with a registering aperture 35 through which the loop 36 of the book back 37 may project. In this instance, the key 38 passing through the clearance slot 39 overlies the tongue 33 and passes beneath the loop. In this manner, the assembly is locked to the book back.

It is not necessary or desirable that the hooked margins of the spring back 32 or the hooked margins of the cover plate 41 should engage the tongue 33 and consequently, the tongue is made narrower than is the previous type.

Reference to Figs. 4 and 6 will show that the toggle plates 10 and 11 bear transverse slots 42 and 43 cut adjacent their ends. A booster lever 44 comprises a thumb arm 45, a fulcrum section 46, and an operating or lifting arm 47 which is turned downwardly adjacent its end to form the necked portion 48 and a head 49. A support and fulcrum for the booster lever is formed by the lower wall of the slot 51 cut through the end closure 19. For appearance and sometimes to add stiffness to the lighter gauges of metals, the thumb arm is transversely curved as indicated. In this instance, the lever is pivoted only at the points 52 and 53, but if the fulcrum section 46 be flat, the lever is pivoted along a line contact, as shown in Figs. 10 and 13.

Two methods of assembly may be adopted: The booster lever 44 may be placed in position through the slot 51 with its necked portion 48 engaged by the slots 42 and 43 of the toggle plates and the margins, either of the spring back or cover plate type, may then be crimped or rolled down over the edges of the toggle plates.

By the other method, the toggle plates 10 and 11 are inserted in springs already formed and are then pried apart sufficiently to allow the insertion of the neck 48 into the slots 42 and 43. In either case, as indicated in Fig. 4, the slots 42 and 43 receive the neck portion 48, and the extensions or wings 54 of the thumb arm 45 lie across the face of the closure 19. Since the booster lever is locked in position by its engagement with the toggle plates, and the supporting element 18 is prevented from having any longitudinal movement by the wings 54, 54, a complete sub-assembly is formed which may be shipped without danger of losing parts.

In the various figures, the cover engaging portion 22 (in Fig. 2) is shown as placed either above or beneath the cover plate. I prefer to place the shoulder 22 beneath the cover plate when this has not sufficient stiffness to prevent it being deformed by the

careless application of pressure, for operators frequently press the ends of the binder instead of the thumb arm. I prefer to form the shoulder 22 so that it overlies a part of the toggle plates 10 and 11. Since the cover 70 16 is flexible and the support 18 is rigidly locked to the book back, a sharp pull upon the rings might cause the support to slide out from engagement with the hooked margins 14 and 15 if the upward movement of 75 the metal were not arrested by the contact of the toggle plates and the shoulder.

Various modifications of form of both booster lever and support are illustrated in Figs. 7 to 14. In Fig. 7, the booster lever 55 is provided with a thumb arm 56, a definite fulcrum section 57, a connecting arm 58, and a lifting arm 59 which is arranged to pass beneath the toggle plates and to lift them. In this instance, the narrowed portion 61 and the head 62 form locking means only and are not called upon to carry any of the operating load.

The booster lever may be inserted from the back of the support outwardly rather than from the front inwardly, as shown in Figs. 9 to 14. In Fig. 9, the support is provided with two small inwardly turned lugs 63 and 64 which take the place of the shoulder 22, previously described. The booster lever 65 is pivoted along the upper margin 66 of the support and is retained in position by the engagement of its downwardly turned lifting arm 67 with the slots 68, 69 cut in the toggle plates. Lugs 71 and 72 protruding laterally 100 from the booster in line with its fulcrum engage with the vertical portions of the lugs 63 and 64 and prevent the lateral displacement of the support 73. As is indicated in Fig. 12, the form of support may be that originally shown, and in this case the booster lever is first assembled by passing its thumb arm 74 through the slot 75. The booster may also be arranged to pass across the ends of the toggle plates and then beneath them lifting 110 the plates by contact of the lifting arm 76 with the under faces 77 of the toggle plates, as is shown in Figs. 13 and 14.

What I claim, therefore, is:

1. In a loose leaf binder, a plate arched 115 transversely with the crown up and the sides turned inwardly, prong-bearing toggle members articulated at their adjacent edges to form a toggle joint and having their remote edges mounted to rotate on the inturned sides 120 of the plate and bearing a slot adjacent their ends, a fitting extending into the end of the arch and engaging with the inturned sides of the plate, and a booster lever fulcrumed on the fitting and having one arm extending 125 through the slot and cooperating with the toggle joint at a slot to open the prongs.

2. In a loose leaf binder, a plate arched transversely with the crown up and the sides turned inwardly, prong-bearing toggle mem- 130

bers articulated at their adjacent edges to form a toggle joint and having their remote edges mounted to rotate on the inturned sides of the plate and bearing a transverse slot adjacent their ends, a fitting comprising a body member engaging with the inturned sides of the plate and adapted to cooperate with attaching means for a cover, an upturned end on the body member and a booster lever fulcrumed on the end of the fitting and having an arm passing through the slot and cooperating with the toggle members to open the prongs.

3. In a loose leaf binder, a plate arched transversely with the crown up and the sides turned inwardly, prong-bearing toggle members articulated at their adjacent edges to form a toggle joint and having their remote edges mounted to rotate on the inturned sides of the plate and having transverse slots adjacent their ends, a fitting comprising a body member engaging with the inturned sides of the plate and adapted to cooperate with attaching means for a cover, an upturned end on the body member and a booster lever extending through a slot in the upturned end and having one arm extending through the slots in the toggle plates and beneath the plates to lift them.

30 4. A loose leaf binder having an arched spring, toggle plates supported in the hooked margins of said spring and having a transverse slot adjacent to their ends, a booster support having a tongue extending beneath the toggle plates and an end closure for the binder mechanism, a booster lever pivoted upon the closure, a portion of the lever disposed against the outer face of the closure to prevent displacement of the mechanism, and 35 a portion of the lever engaged by the slots in the toggle plates.

5. In a loose leaf binder, a pair of articulated toggle plates, each having a transverse slot adjacent to one end, a spring engaging 45 the outer margins of said plates, a booster lever fulcrumed above the plates and having an arm extending across the ends of the plates and then under said plates to lift them, a portion of said arm passing through 50 the slots and retaining the lever in position thereby, and a support for the lever having a tongue parallel to the axis of the binder and an end portion normal thereto.

6. In a loose leaf binder, a support, a 55 booster lever fulcrumed in a transverse slot in the support, an operating arm of the lever extending inwardly beyond the slot and a retaining element on said arm engaged by the toggle plates of the binder.

60 7. In a loose leaf binder, a pair of articulated toggle plates, each having a transverse slot adjacent to one end, a spring engaging the outer margins of said plates, a booster lever having a portion of its operating arm 65 extending through said slots and retained

thereby, a support for the lever substantially closing the end of the binder and having a tongue overlying the book back within the binder, and a head forming the end of said arm adapted to engage the under surface of 70 the toggle plates and to lift them.

8. In a loose leaf binder, a pair of articulated toggle plates each having a transverse slot adjacent one end, a support for a booster lever having a tongue lying within the binder and a lever support at an angle thereto, 75 a booster lever fulcrumed upon the support, and an arm upon the lever engaged by the slots.

9. In a loose leaf binder, a booster lever 80 having a portion adapted to pass through a pair of articulated toggle plates and to lift said plates, a support for the lever comprising a tongue and an end closure, means to pivot the lever upon the support, and 85 means to retain the support within the binder.

10. A loose leaf binder having a spring back, articulated toggle plates mounted in the spring back, a booster support having a tongue extending inwardly beneath the toggle plates and above the spring back, a booster lever pivoted on the booster support above the toggles and having a thumb arm and an operating arm, a reduced portion on the operating arm passing through the toggles and a head upon said arm adapted to lift the plates.

In testimony whereof I affix my signature.
JAMES C. DAWSON.
